GAME APPARATUS

Douglas T. Hawkes, Victoria, British Columbia, Canada

Application February 16, 1953, Serial No. 337,165

4 Claims. (Cl. 273—134)

This invention relates to game apparatus for amusement purposes.

This game is intended to simulate racing, and it may represent races between horses, cars, or any other racing animal or vehicle.

The game apparatus comprises, in combination, indicia-determining means, a plurality of markers, and a game board having a plurality of courses indicated thereon bearing indicia corresponding to those on the indicia-determining means, and an elongated points- or odds-indicating strip positioned at right angles to the courses. One or more playing areas may be associated with the board and, if desired, they may form part of the board.

For the sake of convenience, the game apparatus will be described in connection with horse racing. Each marker represents a horse, and there is a horse for each course on the board. The indicia-determining means are used to determine the progress of each marker along its course, while each player indicates in the playing area the marker or horse he thinks will come in first, second or third in the race. Some means may be provided for indicating the progress or lack of progress of each player in the game. For example, tokens, such as stage money, beans, matches, or the like, may be used by the players for the purpose of placing wagers on the horses. The odds-indicating strip is used to determine the odds on the various horses in a manner hereinafter described. The arrangement of the above elements and the particular manner of using the game apparatus will be understood by the following detailed disclosure of the preferred embodiment illustrated in the accompanying drawings, in which,

Figure 1 is a plan view of a preferred arrangement of game board with one end broken off,

Figure 2 is an enlarged sectional view taken along the line 2—2 showing one manner of holding the elongated odds-indicating strip to the game board,

Figure 3 is an example of a type of marker representing a racing animal or vehicle that may be used on one of the courses as the game is played, and

Figure 4 shows examples of playing cards that might be used with the apparatus as indicia-determining means.

Referring to Figure 1 of the drawings, 10 is a game board formed of any suitable material, such as paper, cloth, cardboard, wood, or the like. This board is divided into a playing surface 11 and one or more playing areas 12, there being two of these areas illustrated in the drawing. The playing surface 11 includes a plurality of parallel courses 13, each of which is divided into an equal number of spaces 14. Each course is identified by a suitable form of indicia which, in the illustrated example, is a numeral designated by the reference character 15. The courses 13 represent the paths followed by horses in a race.

A plurality of markers 18 are provided, see Figure 3, one for each course 13. These markers bear symbols or indicia corresponding to those of the courses so that

2

if the courses are indicated by the numbers one to seven, the markers would also bear the numbers one to seven.

Each playing area 12 is divided into a plurality of sections, there being one or more of these sections for each course 13, and the section or sections for each course bear the identifying indicia of its course. For example, each of the playing areas may be divided into a plurality of sections 20, one for each course, representing first or "win," a plurality of corresponding sections 21 representing at least second or "place," and a plurality of sections 22 representing at least third or "show." Sections 20, 21 and 22 for course 1 and, consequently, horse or marker 1, each bear the numeral 1; sections 20, 21 and 22 for course 2 and marker or horse 2, bear the numeral 2; and so on.

The points- or odds-indicating strip 25 extends across the playing surface 11 of the game board at either end of the courses 13. This strip may be just laid across the board, but it is preferably slidably held in position thereon. For this purpose, one or more loops 26 may be positioned on the surface of the board, in which case the strip slidably extends under these loops. The strip is divided into a plurality of sections 28 throughout its length, the width of each section being substantially equal to the width of a course 13. Each section 28 has a number 29 therein representing odds, as will hereinafter be more fully described. One of the sections near the centre of the strip, for example, section 30, bears one or two numbers which are higher than those of the other sections. In this example, section 30 includes the numerals "10" and "15."

If desired, a plurality of additional sections 34 representing "one-two" sections may be placed on the board. In this example, the sections 34 are located in the playing area 12 around the group formed by the other sections thereof. Each section 34 bears two numbers 35, such as "1-2," "1-3," and the like.

As previously stated, indicia-determining means are provided for regulating the progress of the markers 18 along the courses 13. This may be a spinning wheel, specially printed cards, or dice, or the like, each bearing indicia corresponding to the indicia of the courses and markers or horses. As playing cards are readily available, it is preferable to use such cards as the indicia-determining means. Figure 4 shows a plurality of cards 38 which may be used for this purpose. If the courses 13 are designated by the numbers "1-7," all the cards bearing the numbers 1 (ace) to 7 of at least two decks of cards are used. If cards from two decks are used, there will be eight cards of each number, that is, eight twos, eight threes, etc. As there are ten spaces 14 in each course 13 of the illustrated example, some way must be worked out to enable each marker 18 to move the full length of its course with the limited cards available. For example, each heart or diamond card may call for a move of one space for a marker, each club card a move of two spaces, and each spade card a move of three spaces.

When a game is about to be started, the markers 18 with the numerals "1-7" thereon are placed on the spaces at the beginning of the courses bearing the corresponding numbers. The horses are now ready for the race. The deck of cards 38 may be cut to indicate the position of the odds strip 25. If a card bearing the number 5 is turned up, the section 30 of the strip is placed opposite course number 5, as shown in the drawing. The rules of the game may be such that if the card cut is black, the odds to win would be fifteen to one, whereas if the card is red, the odds would be ten to one. This means that if the horses indicated by marker 5 were to win, these odds would be paid. This horse would be considered a "long

shot." Suitable provision may be made in the rules for the odds if this horse comes in second or third (place or show), and these may be three to one and two to one respectively. The indication of the "long shot" by the odds-indicating strip as described above sets the sections 28 opposite the other courses, thereby automatically setting the odds for the horses of their respective courses should they win. With the strip 25 in the position shown in Figure 1, if horse number 6 were to win, the odds would be four to one, while they would be five to one if horse number 2 came in first. The place and show odds for the horses other than the "long shot" would also be set by the rules and may be two to one and one to one, respectively.

Before the odds are set by the strip 25, the players place their wagers in the desired sections 20, 21 and 22. For example, if a player bets that number 3 horse will win, he would place his wager in the section 20 bearing the numeral 3. On the other hand, if he thinks number 3 horse will place or show, he will place his wager in the appropriate section 21 or 22 bearing the numeral 3. A place wager wins if the horse comes in first or second, and a show bet if the horse comes in first, second or third. If the player wishes to bet the one-two, he will place his wager in a selected section. By this, he is designating the number-combination of the two horses that will first cross the finishing line. For example, if he selects the section with 3-7 in it, this means he hopes that horses 3 and 7 will finish first and second, but it does not matter which of these two horses comes in first and which comes second. The odds for a winning combination such as this will be set by the rules, and may be, say, sixteen to one.

The game may be played in various ways. One player may act as banker and dealer. Once all the wagers have been made and the odds determined by the positioning of the odds tape, the dealer, after shuffling the cards turns them up one at a time. If a two of diamonds is turned up, marker number 2 is moved forward one space along its course 13, if a five of spades is turned up, marker number 5 is moved along three spaces in its course. This is continued until the first, second and third horses arrive at the opposite end of their respective courses. The banker then collects all losing wagers and pays off the winners in accordance with their selections and the odds of the race.

The banker may act on his own behalf or on behalf of all players. In the latter case, the fund of the bank is made up by a contribution from each player. The banker also places his own wagers, and if the bank accumulates an excess of tokens, some of these may periodically be divided amongst the players as dividends. Should the bank fund become depleted, the players would be assessed an agreed number of tokens to restore it. At the end of the game, the bank fund would be divided between the players.

The winner of the game may be the player who has the most tokens at the time another player has lost all of his, or at a predetermined time limit, or at the end of the evening.

What I claim as my invention is:

1. A game apparatus comprising, in combination, a game board having a playing surface with a plurality of parallel courses bearing indicia thereon, each of said courses being composed of a number of marked spaces, indicia-determining means, the indicia on said indicia-determining means being the same as the course indicia,

markers for the courses bearing the indicia of the latter, and an elongated strip extending across said game board and transversely of the courses near the end thereof, said strip being movable relative to the game board and having numbers side by side thereon to indicate the points attributed to each course at a selected position of said strip in relation to the courses, and the numbers of said strip being so arranged that when one is in line with a course, the others are aligned with other courses.

5 10 15 20 25 30 35 40 45 50 55 60 65 70 75 80 85 90

2. A game apparatus comprising in combination, a game board having a playing surface with a plurality of parallel courses bearing indicia thereon, each of said courses being composed of a number of marked spaces, indicia-determining means, the indicia on said indicia-determining means being the same as the course indicia, a marker to be moved along each course, a plurality of loops parallel to one another and connected to said game board, and an elongated strip extending across said game board and transversely of the courses near the end thereof, and held thereon by said loops, said strip being slideable in said loops and having spaced numbers thereon arranged longitudinally of its length to indicate the points attributed to each course at a selected position of said strip in relation to the courses, and the numbers of said strip being so arranged that when one is in line with a course, the others are aligned with other courses.

3. A game apparatus comprising, in combination, a game board having a playing surface with a plurality of numbered parallel courses thereon, each of said courses being composed of a number of marked spaces, a pack of numbered playing cards, the numbers on said playing cards being the same as the numbers on said courses, a marker to be moved along each course, said markers bearing the numbers of the courses, and an elongated strip extending across said game board, said strip being movable relative to the game board and having spaced numbers thereon arranged longitudinally of its length to indicate the points attributed to each course at a selected position of said strip in relation to the courses, and the numbers of said strip being so arranged that when one is in line with a course, the others are aligned with other courses.

4. A game apparatus comprising, in combination, a game board having a playing surface with a plurality of parallel courses bearing indicia thereon, each of said courses being composed of a number of marked spaces, indicia-determining means, the indicia on said indicia-determining means being the same as the course indicia, markers for the courses bearing the indicia of the latter, and an elongated strip extending across the game board adjacent an end of the courses and being movable relative thereto, said strip being divided into a plurality of sections bearing points-indicating numbers, and said strip being movable into different positions to place one of its sections at the end of each course.
